UNITED STATES PATENT OFFICE

165,338

THREAD PICKING AND SEAM RIPPING
IMPLEMENT

Clara E. McNutt, Toledo, Ohio

Application July 26, 1950, Serial No. 11,402

Term of patent 14 years

(Cl. D3—19)

To all whom it may concern:

Be it known that I, Clara E. McNutt, a citizen of the United States of America, residing at 1802 Cherry St., Toledo 8, Ohio, have invented a new, original, and ornamental Design for a Thread Picking and Seam Ripping Implement, of which the following is a specification, reference being had to the accompanying drawing, forming part thereof.

Referring to the drawing:

Fig. 1 is a side elevational view of a thread picking and seam ripping implement in closed position, showing my new design;

Fig. 2 is a view of the device, looking from the top of Fig. 1;

Fig. 3 is a distributed view of the device in open position;

Fig. 4 is a view on the line IV—IV, Fig. 3;

Fig. 5 is a view on the line V—V, Fig. 3; and

Fig. 6 is a view on the line VI—VI, Fig. 3.

I claim:

The ornamental design for a thread picking and seam ripping implement, substantially as shown.
CLARA E. McNUTT.
